UNITED STATES PATENT OFFICE.

GEORGE C. MOORE, OF WESTERLY, RHODE ISLAND.

GARMENT SUPPORTER.

Application filed February 23, 1926. Serial No. 90,028.

The invention relates to the garment-engaging and holding elements or attachments of garment supporters, as for example stocking supporters.

One general object of the invention is to enable the present kinds of metal loop-shaped engaging and holding elements or attachments to be eliminated. Another is to enable engaging and holding elements or attachments of less expensive character than those at present employed in practice to be used instead of the latter. Another object of the invention is, in the case of a garment supporter having an anchor-neck adapted to be enveloped by a portion of the garment which is engaged thereby, and a flexible binder connected above with the garment-supporter and adapted to be wrapped around the said enveloping garment-portion and the anchor-neck, to provide for adjustment of the binder in the direction of the length thereof, to enable a worn portion thereof to be shifted into an idle relation and an unworn portion of the binder to be brought into position for use, to thereby distribute wear and prolong the period of usefulness of the garment-supporter. Another object of the invention is to provide against relaxation and loosening of the portion of the binder which is wrapped about the enveloping garment-portion and anchor-neck, in consequence of movements of the wearer.

Illustrative embodiments of the features of the invention are shown in the accompanying drawings.

In the drawings,—

Fig. 1 is an elevation of a stocking supporter presenting the various features of the invention in one form of embodiment.

Fig. 2 is an edge view thereof.

Fig. 3 is an elevation showing the said supporter in engagement with the upper portion of a stocking.

Fig. 4 is a view partly in vertical section on line 4, 4, of Fig. 3.

Fig. 5 is an edge view of the anchor of Figs. 1 to 4.

Fig. 6 is an elevation of a second form of embodiment.

Fig. 7 is an edge view thereof.

Fig. 8 is an elevation showing the supporter of Figs. 6 and 7 in engagement with the upper portion of a stocking.

Fig. 9 is a view partly in vertical section on line 9, 9, of Fig. 8.

Fig. 10 is a side elevation of another form of embodiment.

The supporters shown in the drawings are of the well-known type comprising a band-like suspender portion, composed of web material, having combined with the lower end thereof the elements or attachments which are employed for the purpose of engaging and holding the top of a stocking. In the case of the illustrated supporters, the web-portions 18 are composed of elastic webbing. The terminal web-portions 2, 21, 211, are composed of inelastic web material.

The necked anchor 1 in the case of the supporter shown in Figs. 1 to 5 is a flat piece of suitable firm material having above the head 19 thereof a neck 11, Fig. 1, produced by indentations 12, 12, in the opposite margins of the said piece, and having below the said neck rounded surfaces 13, 13, of the said head extending laterally in opposite directions. The connection of the said anchor with the suspender portion of the supporter is provided for in Figs. 1 to 4 by means of a transverse slot 14 in the upper portion of the anchor, which slot is occupied by a loop 2 of web material at the lower end of the said suspender portion. When incorporated in a stocking supporter this anchor 1 is curved transversely, as shown in Fig. 5, in order that it may conform to the curvature of the leg of the wearer and fit more closely to the surface of the latter at the side-margins of the anchor. The breadth of the anchor, its flatness, and its curvature transversely, all combine to permit an overlying garment to lie smoothly and without observable projection or bulge over the anchor, so that the presence of the anchor is not noticeable even when thin and scanty apparel is worn.

The necked anchors shown in Figs. 6 to 10 have flat disk-like heads. In Figs. 6 to 9 the head 15 is a flat button that is convex at its outer face, and formed with a central convexity or boss at its back, it being tapered radially to a thin edge, and it being fastened by stitches 151 to the web-portion 21 at the lower end of the suspender portion of the supporter. The projecting convexity or boss of the back, and in some cases the portions of the fastening threads which extend between the head and said web-portion constitute a neck. In Fig. 10 the head, 152, is formed at its back with a boss 153 receiving a tubular

rivet 154 by which the head is attached to the portion 211 of the suspender. The boss constitutes the neck in this instance. The breadth and convexity of the anchors of Figs. 6 to 10, combined with the thinness thereof, secure the same results that have been mentioned in connection with the anchor of Figs. 1 to 4.

The flexible binder 3, Figs. 1 to 4, and 31, Figs. 6 to 10, is shown as a piece of cord, round in cross-section, which is adapted to be wrapped around the anchor-neck so as to enclose said neck and bind to it a portion 4 of a stocking which has been applied over the anchor-head and neck as in Figs. 3, 4, 8 and 9. The binder, as will be obvious, may vary more or less as regards material, shape in cross-section, and the like particulars. Preferably I make use of a longitudinally elastic binder, an acceptable form of which is composed of an elastic core and a suitable covering. A longitudinally elastic flexible core of any suitable known material may be provided. Preferably I employ a rubber core. The covering may vary in character and may be applied variously. It may consist of threads, wrapped, woven or braided upon the core. When a core is employed the covering protects the rubber from wear and other injury, and saves it more or less from the effects due to unprotected exposure to the atmosphere. An advantage of a longitudinally elastic binder is that it stretches more or less in being wrapped around the neck of the anchor and the applied portion of stocking, which facilitates the operation of wrapping. Then when left free to contract it does so, until all excess length is taken up so that the binder tightens upon the neck and said applied portion embracing the latter more securely and maintaining a secure hold thereon.

The preferred form of binder is that of a loop, as in the drawings. In Figs. 1 to 4 this is interlooped with the loop 2 of web material at the lower end of the suspender portion, and thereby retained in connection therewith. In Figs. 6 to 10 the material of the loop passes through holes in the web-portion 21, 211. Such holes are shown bushed by means of tubular rivets 22, 221, to reinforce the margins of the holes as well as facilitate play of the binder within and through the holes. It is advantageous to employ an endless binder, either made initially in endless form or rendered so by binding or knotting together ends of a section of material primarily of so-called continuous length. The loop may be wrapped as shown in Figs. 3, 4, 8 and 9 around the anchor-neck and the portion of stocking applied thereto, or may simply be engaged under the neck and said portion of stocking. The binder is of a length permitting it to pass two or more times around the anchor,

so that its hold upon the garment is exceedingly certain and effective.

In the case of a binder in the form of a complete loop, interlooped as in the drawings, the loop will shift around automatically in being manipulated, or may be shifted around intentionally. This shifting will distribute the effects of wear, thereby prolonging the period of usefulness of the loop and of the supporter of which it constitutes a part.

In the case of the garment-supporter shown in Figs. 1 to 5, the flat piece or plate of which the body of the device is formed, being inflexible, it follows that the inflexibility of said piece or plate intermediate the point of connection above of the binder to the garment-supporter, and the anchor-neck, obviates bending of the said body in consequence of the movements of the wearer, thereby preventing relaxation and loosening of the portion of the binder which is enwrapped about the anchor-neck. Consequently whether the wearer stoops forward or not, the binder is always tight around the anchor-neck.

The construction of the suspender portion of garment supporters provided with necked anchors and flexible binders such as aforesaid may vary in practice, and the invention in its broad phases is not restricted to the precise necked anchors and flexible binders which are shown and described herein.

An advantage of an elastic flexible binder looped around a necked anchor and applied portion of a stocking, substantially as shown in the drawings hereof, is that when vertical strain occurs the portion or portions of the binder which are located at the back of the anchor will yield, thereby accommodating the pull and lessening the tendency to rupture of the fabric of the stocking.

The upper end portions of the supporters shown in the drawings have been omitted, as unnecessary to be shown. They may be of any approved character and, when necessary, connection with any convenient upper garment, such for instance as a corset, may be provided for in any suitable manner.

What is claimed as the invention is:—

1. A garment-supporter comprising suspending means, a plate connected above with said suspending means and below provided with an anchor-neck adapted to be enveloped by a portion of the garment which is engaged thereby, and a flexible binder connected with one of said parts above the anchor-neck and adapted to be wrapped in more than one complete turn around the said enveloping garment-portion and the anchor-neck, the inflexibility of said plate intermediate the point of connection of the said binder and the said anchor-neck preventing relaxation and loosening of the enwrapped portion of the binder.

2. A garment-supporter comprising suspending means, a flat anchor-member connected above with said suspending means and provided below with an anchor-neck adapted to be enveloped by a portion of the garment which is engaged thereby, and a flexible binder connected with one of said parts above the anchor-neck, adjustable

lengthwise to present fresh portions thereof for enwrapping about the anchor-neck and 10 the applied garment, and adapted to be wrapped in more than one complete turn around the enveloping garment portion and the anchor-neck.

GEORGE C. MOORE.
